[57] CLAIM

The ornamental design for a combined back scrubber and applicator, as shown and described.

DESCRIPTION

FIG. 1 is a perspective view of a preferred embodiment of the combined back scrubber and applicator;

FIG. 2 an end view thereof;

FIG. 3 is a top planar view thereof;

FIG. 4 right side elevational view thereof, the left side elevational view being a mirror image thereof;

FIG. 5 is a bottom planar view thereof; and,

FIG. 6 is a perspective view of the back scrubber and applicator of FIG. 1 having a scrubber mitt (as shown in phantom line) fitted over the paddle end thereof.

The broken line showing of the scrubber mitt in FIG. 6 is for illustrative purposes only and forms no part of the claimed design.
